UNITED STATES PATENT OFFICE.

HENRY P. PAUL, OF CAMDEN, NEW JERSEY, ASSIGNOR TO FARR AND BAILEY MANUFACTURING COMPANY, A CORPORATION OF NEW JERSEY.

DISINTEGRATOR.

1,018,440.

Specification of Letters Patent.

Patented Feb. 27, 1912.

Application filed September 17, 1908. Serial No. 453,403.

To all whom it may concern:

Be it known that I, HENRY P. PAUL, a citizen of the United States, and a resident of Camden, county of Camden, State of 5 New Jersey, have invented an Improvement in Disintegrators, of which the following is a specification.

My invention has reference to disintegrators and consists of certain improvements 10 which are fully set forth in the following specification and shown in the accompanying drawings which form a part thereof.

The object of my invention is to provide a construction of machine for disintegrating 15 linoleum compound and other substances, which shall embody simplicity, durability, easy repair and rapid cleansing.

My invention consists in a case having at 20 the bottom means for receiving the disintegrated or pulverized materials, combined with a rapidly rotating beater device and a more slowly rotating perforated screen surrounding the beater device and inclosed within the case; further in so forming the 25 case that it consists of two rigid side frames connected by a series of fixed cross bars, and the intervening spaces covered by plates, preferably of sheet metal, whose ends are clamped upon the cross bars by clamping 30 devices carried by the fixed cross bars, whereby said covering plates may be bodily removed to expose the interior structure of the machine; further in forming the revolving screen of two circular flanged end 35 frames, one of which is centrally open to admit the material to be treated, and a sheet metal screen stretched about the circular end frames and having clamping devices on its ends for tightening the screen in position 40 and yet permitting of its easy removal for cleansing or when a screen of a different mesh or size of perforation is required, the said screen being of sheet metal it may be unclamped and drawn out, more or less flat, 45 without dismantling the casing of the machine; further in the construction of disintegrator drum and beaters whereby the latter may be easily replaced when worn without the necessity of removing the drum 50 from the casing; further in the means for simultaneously rotating the beater drum and screen drum in the same direction and at different speeds.

My invention also comprehends details of 55 construction which, together with the fea-

tures above specified, will be better understood by reference to the drawings, in which:

Figure 1 is an end elevation of my improved disintegrating machine; Fig. 2 is 60 sectional elevation of the same; Fig. 3 is a front elevation of the same; Fig. 4 is a front sectional elevation of the hopper end of the machine; Fig. 5 is a sectional plan view of my improved machine; Fig. 6 is a 65 sectional plan view (on a larger scale) of the speed controlling and driving gearing; Fig. 7 is an elevation, with part broken away, showing the construction of the screen drum covering; and Figs. 8, 9 and 10 are 70 sectional views of details.

The general construction of the machine embodies a revolving beater drum having a series of beater arms or blades, combined with an inclosing revolving screen drum 75 open at one end and into which the material to be disintegrated or pulverized is fed from a hopper, the said screen drum acting to continually lift the material and bring it into free position to be struck by the rapidly 80 rotating beaters, an inclosing case surrounding the screen drum and having at its bottom one or more drawers or trays for receiving the pulverized and screened material, power means for rotating the beater 85 drum, and gearing for causing the screen drum to rotate at a slower speed than the beaters, the construction being such that the machine may be fed continuously with material to be disintegrated and the action 90 within the screen drum such that it is subjected to a cleansing action which prevents clogging of its perforations.

A feature of construction of my improved machine which makes it especially advantageous is, that every part of the machine may be exposed for cleaning or repairs without dismantling the fixed portions of the machine, and this result is secured by having the outer case formed with sheet metal 95 removable sections detachably clamped in position, and the screen covering of the screen drum formed of a removable sheet metal screen clamped in position about the cast metal side frames and which may be 100 easily removed and withdrawn, as a sheet, to expose the beaters and inner mechanism.

I will now more specifically describe my improved machine:

2 are the side frames and are of cast iron 110

adapted to stand upright from the floor. These side frames 2 are connected at top and at front and back on the horizontal diameter of the machine by fixed cross bars 3, which are essentially T shaped in cross section so as to form opposite grooved portions on the outside.

37 are sheet metal covering plates having reinforcing bars 39 at their ends, and said 10 ends rest in the grooves of the cross bars 3 and are clamped in position by cross clamp bars 40 and clamping screws 41 screwed into the cross bars 3. In addition to the plates 37, there are two additional covering plates 15 38, similarly reinforced at their upper edges at 39 and clamped in position by the clamp bars 40 and screws 41 (Figs. 2 and 3) and the lower ends of these plates 38 are guided and held in grooves 42 in the side frames 2 20 (Figs. 2, 3 and 10). By this construction, one or more of the covering plates may be removed without disturbing the permanent structure of the case. While I have shown an excellent form of clamping means for 25 holding the plates in position, it is to be understood that I do not restrict myself to this particular means as any other means capable of holding the plates in position may be employed.

30 8 is the beater shaft which extends centrally through the machine and journaled in the bearings 6 and 7 and is provided at one end with the driving belt wheel 9. Secured firmly to this shaft is a hub or drum 35 10 which is provided with four T-shaped sockets at each end into which T-shaped beaters 11 and 12 are received and clamped in position by end heads 13 secured in position by bolts 14 extending through the drum 40 10 and said heads 13, as shown in Figs. 2 and 5. The opposite beater arms 11 are straight, whereas the opposite beaters 12 are curved outward so that their ends travel in 45 a different path from the beaters 11. In this manner the beaters 11 and 12 travel in four parallel planes and are thus distributed transversely of the inclosing screen drum 15, as will be readily understood by reference to Fig. 5. It is evident that beaters may be 50 readily replaced when worn or broken by simply removing the nuts of the bolts 14 and withdrawing the heads 13 from the socketed ends of the beaters. As much wear comes upon the beaters, it is most important 55 that they shall be easy of replacement when necessary.

Surrounding the beater drum and beaters is the screen drum 15, consisting of the cylindrical end plates 16 and 19 and the connecting screen covering 30. Referring to 60 Fig. 5, the end plate 19 has a hub 20 journaled on the shaft 8 and also within the bearing 22 in a support 21 on the frame 2. End plate 16 is open at the center and has a flange 17 which is journaled on a Babbitt

bearing 18 supported by a tubular flange 4 secured upon the inner face of the side frame 2. Both of the end plates 16 and 19 are flanged at their outer ends (Fig. 5) and upon these flanges the perforated sheet metal screen covering 30 is stretched. I prefer that the side edges of this screen covering be left plain (Fig. 7). The ends of the sheet metal, of which the covering 30 is made, are overlapped and respectively 70 provided with flanges 31 and 32 which are connected by tension bolts 33 (Figs. 7 and 8). By clamping the screen covering upon both the end plates 16 and 19, the rotation of the latter will cause the entire screen 75 drum to rotate.

The material to be disintegrated is fed into a hopper 5 on one of the end frames 2 (Fig. 4) and from the hopper it passes through the tubular flange 4 and into the 80 interior of the screen drum 15. The cylindrical flange 4 may be provided with an inclined floor 45, as a continuation of the floor of the hopper, if so desired. In this way the material is delivered within the screen 85 drum and to the beaters with freedom during the normal operation of the machine. By being able to continuously feed the machine, it does not become clogged or over-loaded and hence the rapidly moving beaters 90 have full opportunity of forcibly striking the material with a clean impacting blow as distinguished from pushing or churning it, the result being a rapid and perfect dis-integration at a minimum cost.

Below the screen drum are arranged two drawers 43 and 44, the former receiving the disintegrated and screened material and by which it may be removed at intervals. During the act of removal the machine continues 105 to operate and the material falling from the screen is received in the lower drawer 44. However, the upper drawer may be emptied a half dozen times to each emptying of the lower drawer. The employment of the two 110 drawers enables, however, the operation of the machine to be continuous and hence economical.

As before stated, the screen drum 15 is rotated at a slower speed than the beaters 115 and their shaft 8 and to secure this result, I employ the speed gearing shown in Fig. 6. This speed reducing gearing is made as follows:—The beater shaft 8 has keyed to it a pinion 27, which meshes with a gear of 120 larger diameter 26. This latter gear 26 is keyed to a pinion 24 sleeved on the shaft 25 so that the pinion is rotated at a slower speed than the shaft 8. The pinion 24 is geared to a gear wheel 23 fast upon the hub 125 20 of the screen drum and by which it is rotated. It will be observed that, by means of this gearing, the screen drum is rotated at a considerably slower speed than the beater shaft. Any other form of speed reducing 130

gearing may be used if so desired. As shown, this gearing is inclosed within an oil box consisting of a lower part 28 carrying the bearing 7 and attached to the side frame 5 2, and an upper cap or cover 29 detachably secured in place to keep out the dirt and to prevent escape of the lubricant.

My invention may be used for disintegrating or pulverizing various materials or 10 pounds in a speedy and efficient manner and hence, while I have used it more especially for the disintegration of linoleum compound or mixture preliminary to its being put into the plastic condition, I in no wise intend to 15 restrict myself in the use of my invention.

A most important feature in my improved disintegrator resides in the capacity for quickly changing the screen whereby finer or coarser apertured screens may be em- 20 ployed.

I have shown my invention in the form which I have found most excellently adapted for commercial practice, and while I prefer the same, it is evident that the details 25 thereof may be modified without departing from the spirit of the invention.

Having now described my invention what I claim as new and desire to secure by Letters Patent, is:

1. A screen drum plate for a disintegrator, 30 consisting of a long flexible perforated plate having cross bars secured at a short distance from each end so as to leave portions of the plate beyond the cross bars, and clamping bolts connecting the cross bars for drawing 35 them toward each other and causing the ends of the plate to overlap intermediate of the cross bars.

2. A screen drum plate for a disintegrator, 40 consisting of a long flexible plate having cross bars secured at a short distance from each end so as to leave portions of the plate beyond the cross bars, and the body of said plate between the cross bars being uniformly 45 perforated throughout its length and width with the exception of the surface adjacent to the side edges which is unperforated for a short distance from said edges, and clamp- 50 ing bolts for drawing the cross bars toward each other and causing the ends of the plate to overlap intermediate of said cross bars.

In testimony of which invention, I have hereunto set my hand.

HENRY P. PAUL.
